UNITED STATES PATENT OFFICE.

JOSEPH E. MCGINNESS, OF PITTSBURGH, PENNSYLVANIA.

GOLF-BALL MARKER.

Application filed December 20, 1927. Serial No. 241,306.

My invention consists of an improvement in golf ball markers. It has for its object to provide means for loosely holding a ball and for bringing it into contact with a row of printing type by means of a slidable holder adapted to move the ball rotatably thereover.

The improvement is of the same general kind disclosed in my prior Patent #1,633,536, issued June 21, 1927.

In the present machine the construction is simplified and reduced in number of parts and is modified in various features, adapting it to easy and quick operation.

In the drawings showing the invention:

Fig. 1 is a view of the golf ball marker inside elevation, with the ball in position for marking;

Fig. 2 is a plan view of Fig. 1;

Fig. 3 is a partial view similar to Fig. 1, showing the ball holding frame raised;

Fig. 4 is a cross sectional view on the line IV—IV of Fig. 3;

Fig. 5 is a detail sectional view on the line V—V of Fig. 4; and Fig. 6 is a cross-section showing a modified construction.

The machine as a whole consists of a supporting frame provided with marking means, as type, and a movable ball holder mounted thereabove arranged for sliding and downwardly pressing action against the type, with facility for throwing the ball holder upwardly for insertion and removal.

A main base or supporting portion 2 of any suitable construction is adaptable to be set upon a supporting surface, as a table, by its legs 3, forming a supporting base for the printing type housing 4.

The printing type are adapted to be mounted in a holder mounted on or inserted through the base 2 so as to bring their upper active terminals in a row longitudinally of the machine over which the ball to be marked is progressed.

While the type may be mounted in any suitable manner, I utilize a type holding box or casing 5 inserted downwardly or upwardly through the base 2 and adapted to be held in the housing in any suitable way, as by set screws 6. Casing 5 may be provided with suitable tightening means, as a screw 7, for clamping the type 8 in desired position for printing a name, as the ball is rolled thereover.

By loosening the screws, the type holder

and type may be removed for substitution of a new or different name, as will be readily understood.

A printing ribbon 9 is laid longitudinally along over the top of the printing type, through guides 10, 11, one or both of which may be longitudinally adjustable, extending upwardly around the type housing, as shown in Fig. 1, and leading from an unwinding spool 12 to a winding spool 13. These spools are pivotally mounted at opposite ends of the machine in brackets 14, and spool 13 is provided at one side with a toothed wheel 15 for feeding of the ribbon.

Extending upwardly from base 2 are posts 16 having heads 17 providing bearings for the pair of longitudinally supporting rods 18 for the ball holder. The latter consists of a slidably movable frame or shuttle 19 having lugs 20 mounted on rods 18 at opposite sides for sliding action thereon, in the nature of a cross head.

Pivotedly mounted by a cross pin 21 is the ball holding clamping frame 22. A pair of pressure wheels or spool-shaped rollers 23 having outer enlarged flanges is rotatably mounted in frame 22 by pin 21 and a similar pin 24 respectively, spaced apart to provide the intervening clearance for engagement of the ball between the embracing rollers 23. Frame 22 is provided with an operating handle 25 at its free end, by which the frame may be thrown upwardly on its pivot 21, or lowered down for printing, and the frame has a holding extension 25^a.

A limiting stop 26, in the manner of a sleeve around one of the rods 18, limits movement in one direction so as to ensure bringing the ball into proper initial contact with one end of the series of printing type.

For the purpose of loosely holding the ball in the holding frame I provide resilient loops 27 of wire or the like, extending downwardly from each side of the frame 22 underneath, as shown in Figs. 1 and 4. The ball A may be inserted between the wires for loose mounting, with relation to the rollers 23, so that it may be lowered against the type in proper position for action.

Frame 22 is provided with a pawl or finger 28 loosely mounted at 29 between bearings 30. Pawl 28 engages one of the teeth of wheel 15 in one direction for partial rotation of the wheel by shouldered resistance in its mount-

- ing 29 and freely passes upwardly and backwardly over the wheel in reverse direction, thus moving the printing ribbon a short distance at each operation.
- 5 The ball A is easily inserted and removed by tilting the ball holder upwardly as in Fig. 3, and upon lowering the frame it will rest upon the guide in front of the row of type. Sufficient pressure is exerted downwardly on 10 the ball holder, as it is pushed toward the other end of the machine, wheels 23 riding over the ball which itself is thus caused to roll over the type from one end to the other. At the end of the stroke the ball rides onto the 15 top of housing 11, releasing any engagement with the printing ribbon, and preventing smearing of the ball, and allowing the ribbon to then be fed forwardly without interference by the pawl 28.
- 20 The construction and operation of the machine will be readily understood and appreciated from the foregoing description. It is comparatively simple, easily operated, not liable to get out of order, and capable of rapid 25 operation, with quick change of the printing type.

The machine may be also utilized for printing tennis balls or various other kinds of balls, for which purpose its dimensions would be 30 suitably changed. The particular design, proportions or other details of the invention may also be variously changed or modified by the skilled mechanic to adapt it to different 35 conditions of use, but all such changes are to be understood as within the scope of the following claims.

What I claim is:

1. A golf ball marker comprising a frame provided with a marking device, and a movable ball carrier traversible over the marking device having upper pressure rollers and ball retaining means depending below the carrier.
2. A golf ball marker comprising a frame provided with a marking device, a movable ball carrier traversible over the marking device having upper rollers adapted to application of pressure of the ball against the marking device as it moves thereover, and a ball holder depending from the carrier.
3. A golf ball marker comprising a frame provided with a marking device, and a movable ball carrier traversible over the marking device having looped arms for loosely holding a ball as it is moved over the marking device.
4. A golf ball marker comprising a frame provided with a marking device, and a movable ball carrier traversible over the marking device and movable towards and from the marking device provided with upper pressing rollers.
5. A golf ball marker comprising a frame provided with a marking device, and a movable ball carrier having upper pressure roll-

ers and ball holding means arranged for longitudinal movement over the marking device and also upwardly away therefrom.

6. A golf ball marker comprising a frame provided with a marking device, and a longitudinally and upwardly movable ball carrier arranged for longitudinal movement over the marking device and having a pair of upper concave pressure exerting rollers providing rolling bearings for a ball.

7. A golf ball marker comprising a frame provided with a marking device, a movable ball carrier arranged for longitudinal movement over the marking device and having pressure exerting rollers providing rolling bearings for a ball, and means for loosely holding the ball in operative relation to the rollers.

8. In a golf ball marker, a supporting frame having a group of printing type, a longitudinally movable carriage, and a ball carrier adjustably mounted on the carriage for independent vertical movement having a pair of upper ball engaging rollers.

9. In a golf ball marker, a supporting frame having a group of printing type, a longitudinally movable carriage, a ball carrier adjustably mounted on the carriage having ball engaging rollers, and means for loosely holding the ball in relation thereto.

10. In a golf ball marker, a supporting frame having a group of printing type, a longitudinally movable carriage, a ball carrier adjustably mounted on the carriage having ball engaging rollers, and a pair of resilient looped arms for loosely holding the ball in relation to the rollers.

11. In a golf ball marker, a supporting frame having a longitudinally arranged group of printing type, a carriage movable longitudinally thereover, and a ball holder on the carriage having pressure exerting rollers and ball holding means.

12. In a golf ball marker, a supporting frame having a longitudinally arranged group of printing type, a printing ribbon thereon, a carriage movable longitudinally thereover, and a ball holder on the carriage having pressure exerting rollers and ball holding means.

13. In a golf ball marker, a supporting frame having a longitudinally arranged group of printing type, a printing ribbon thereon, a winding and unwinding ribbon reel, a carriage movable longitudinally over the ribbon and type having a shifting device for the winding reel, and a ball holder on the carriage having pressure exerting rollers and ball holding means.

14. In a golf ball marker, a supporting base provided with a removable type holder and means holding it on the base, an upper trackway, a carriage longitudinally movable along the trackway, and a ball holder pivoted on the carriage provided with ball engaging roll-

ers and a pair of oppositely located resilient ball retaining loops.

15. In a golf ball marker, a supporting base provided with a removable type holder and means holding it on the base, a printing ribbon and a winding and an unwinding reel therefor arranged in alinement with the type, an upper trackway, a carriage longitudinally movable along the trackway and having a shifting device for the winding reel, and a ball holder pivoted on the carriage provided with ball engaging rollers and a pair of oppositely located ball retaining wire loops.

16. In a golf ball marker, a supporting base provided with a removable type holder and means holding it on the base, an upper trackway, a carriage longitudinally movable along the trackway, means limiting the movement of the carriage, and a ball holder pivoted on the carriage provided with concaved ball engaging rollers and a pair of oppositely located resilient ball retaining loops.

17. The combination with a frame having an upper pair of parallel rods and a longitudinally movable carriage thereon having an upwardly and downwardly movable ball holder adapted to roll a ball over printing de-

vices; of a type holder mounted in the frame having at each end a movable or adjustable ribbon-retaining guide, an unwinding and a winding ribbon reel beyond each of said guides, a toothed wheel on the winding reel, and a pivoted abutment on the carriage for engaging the toothed wheel.

18. A golf ball marker having printing type and a superimposed carriage movable thereover having a pivotally mounted ball holder provided with a pair of concaved bearing rollers, ball holding loops, and a handle providing for movement and pressure of the carriage and ball over the type.

19. A golf ball marker having printing type and a superimposed carriage movable thereover having a pivotally mounted ball holder provided with a pair of concaved bearing rollers, ball holding loops, and a handle providing for movement and pressure of the carriage and ball over the type and for throwing the ball holder upwardly on its pivotal mounting.

In testimony whereof I hereunto affix my signature.

JOSEPH E. McGINNESS.
